Primary Examiner — Susan Moon Lee

(57) **CLAIM**

I claim the ornamental design for an apparatus for use by animals including dogs, as shown and described.

DESCRIPTION

FIG. 1 is a right side perspective view of an apparatus for use by animals including dogs, in accordance with the present design;

FIG. 2 is a front view thereof;

FIG. 3 is a rear view thereof;

FIG. 4 is a left side view thereof;

FIG. 5 is a right side view thereof;

FIG. 6 is a bottom view thereof; and,

FIG. 7 is a top view thereof.

The broken lines depict unclaimed features of the apparatus for use by animals including dogs, depicted for illustrative purposes only.

1 Claim, 5 Drawing Sheets
